ANTENNA CONSTRUCTION

Wesley C. Mock, Jr., Olmsted Falls, Ohio

Application May 20, 1948, Serial No. 28,216

4 Claims. (Cl. 250—33)

1

This invention relates, as indicated, to antenna construction, but has reference more particularly to a high frequency antenna construction which is particularly adapted for television purposes.

A primary object of the invention is to provide a flexible system of antenna construction, which utilizes a minimum number of types of interchangeable components, which may be assembled into antenna of many useful configurations.

Another object of the invention is to provide elements for antenna construction which are of novel form and construction, and which can be manufactured in commercially desirable quantities, at low cost, by conventional manufacturing methods.

A further object of the invention is to provide a novel antenna block which lends itself to such a flexible system of construction.

Other objects and advantages of the invention will be apparent during the course of the following description.

In the accompanying drawings, forming a part of this specification, and in which like numerals are employed to designate like parts throughout the same,

Fig. 1 is an exploded view of an antenna of the folded dipole type, embodying the principal features of the invention;

Fig. 2 is an elevational view of one face of a typical antenna block, as used in the construction shown in Fig. 1;

Fig. 3 is a top plan view of the block shown in Fig. 2;

Fig. 4 is an elevational view of the face of the block which is opposite that shown in Fig. 2;

Fig. 5 is an exploded view of an antenna comprising a pair of crossed folded dipoles arranged to produce an omnidirectional pattern, and embodying the principal features of the invention, and

Fig. 6 is an exploded view showing coupling means employed where a mast extension is to be used.

Referring to Figs. 1 to 4 inclusive of the drawings, there is disclosed an antenna of the folded dipole type, comprising a tubular mast 1 embraced by a ground clamp 2 to which a ground strap 3 is secured, as by means of a screw 4 and nut 5.

The mast 1 is surmounted by a metallic mast block 6 having a cylindrical projection 7 which is telescopically insertable in the upper end of the mast and is adapted to be fastened to the latter by means of a screw 8 and nut 9. Extending through the block 6 is a long screw to one

end 10 of which an antenna block 12 is secured, the block 12 being similar in size to the block 6, but made of electrically insulative material. The block 12 is provided at opposite faces thereof with posts 13 formed integrally with the block 12, and to which tubular antenna rods 14 are secured as by means of screws 15 and nuts 16.

Secured in threaded engagement with the opposite end 11 of the screw is an antenna block 17, 10 similar in all respects to the block 12, but made of a metallic material. The block 17 is provided at opposite faces thereof with posts 18, formed integrally with the block, to which tubular antenna rods 19, similar to the rods 14, are secured, 15 as by means of screws 20 and nuts 21.

Antenna end plates 22 are secured to the ends of the tubes 14 and 19, as by means of screws 23.

Secured to the portions of the ends 10 and 11 20 of the screw which extend beyond the blocks 12 and 17 are tubular spreaders 25. Metallic blocks 26, similar to the block 17 are secured to the spreaders 25, as by means of screws 27. Each of the blocks 26 is provided with posts 28, extending from opposite faces thereof, and tubular antenna rods 29 are secured to these posts, as by 25 means of screws 30 and nuts 31.

A screw stud 32 is threadedly secured to the upper face of the block 6, and a lightning arrester 33 is secured to this screw stud.

The antenna, as thus described, is of the folded dipole type, and includes parasitic elements, in the form of the spreaders 25 and rods 29, which function to increase the directivity of the antenna.

35 In the assembly of the various parts of the antenna, the blocks 12, 6 and 17 are brought into direct contact with each other, after which the rods 14 and 19 are secured to the blocks 12 and 17, 40 and the end plates 22 then secured to the rods 14 and 19. To facilitate proper alignment of the blocks 12, 6 and 17 with each other, the blocks are provided in one face thereof with a pair of dowel openings 34 and 35, and in the opposite face thereof with a dowel pin 36 and a dowel opening 37. This arrangement of dowel and dowel openings permits one of the blocks to be rotated 90 degrees relatively to an adjacent block and locked or doweled to the latter.

45 Referring to Fig. 5 of the drawing, there is disclosed an antenna consisting of a pair of crossed folded dipoles arranged to produce an omnidirectional field pattern.

The antenna comprises a tubular mast 40 50 braced by a ground clamp 41, to which a ground

55

strap 42 is secured, as by means of a screw 43 and nut 44.

The mast 40 is surmounted by a metallic mast block 45 having a cylindrical projection 46 which is telescopically insertable in the upper end of the mast and is adapted to be fastened to the latter by means of a screw 47 and nut 48.

Secured to the block 45 and extending vertically therefrom is a long screw 49, to which the blocks constituting the antenna rod supports are threadedly secured. Immediately above the block 45, a block 50 is disposed, made of electrically insulative material and provided at opposite faces thereof with posts 51 formed integrally with the block, and to which tubular antenna rods 52 are secured, as by means of screws 53 and nuts 54. Immediately above the block 50, a block 55 is disposed, also made of electrically insulative material and provided at opposite faces thereof with posts 56 formed integrally with the block, but disposed with their axis at right angles to the axis of the posts 51. Tubular antenna rods 57 are secured to the posts 56, as by means of screws 58 and nuts 59.

Immediately above the block 55, a block 60 is disposed, which is similar in all respects to the block 50, but made of a metallic material, the block being provided with posts 61 to which tubular antenna rods 62 are secured, as by means of screws 63 and nuts 64.

Immediately above the block 60, a metallic block 65 is disposed, which is similar to the block 60, but has the posts 66 thereof extending with their axis at right angles to the axis of the posts 61. Tubular antenna rods 67 are secured to the posts 66, as by means of screws 68 and nuts 69.

End plates 70 are secured to the ends of the rods 52 and 62, as by means of screws 71, while end plates 72 are secured to the ends of the rods 57 and 67, as by means of screws 73.

A lightning arrestor 74 may be secured to the screw 49, the lightning arrestor, in this case, functioning also to clamp all of the blocks to the mast.

In assembling the various parts of this antenna, the blocks 45, 50, 55, 60 and 65 are brought into direct contact with each other, after which the rods 52, 62, 57 and 67 are secured to the blocks, and the end plates 70 and 72 are then secured to such rods.

In Fig. 6, means are disclosed for providing a mast extension. The tubular mast 80, in this case, is surmounted by a block 81 which has a cylindrical extension 82 which fits into the upper end of the mast. The block 81 has threadedly secured thereto a screw stud 83 to which an extension collar 84 is threadedly secured. The collar 84 has a circular opening in its upper face adapted to receive the reduced extension 85 of a mast extension 86. The mast extension 86 is locked to the collar 84 by means of a set screw 87.

It is apparent from the foregoing that by the use of a single basic block of novel form, many types of antenna may be constructed, ranging from simple dipole types to multi-element or complex arrays, including parasitic elements, the only elements requiring change for different operating frequencies being the antenna rods and spreaders.

The use of such blocks, in combination with the screws provides a highly flexible system of construction, permitting assembly into antennae of many useful configurations.

It is to be understood that the form of my invention, herewith shown and described, is to be taken as a preferred example of the same, and

that various changes in the shape, size and arrangement of parts may be resorted to, without departing from the spirit of my invention, or the scope of the subjoined claims.

Having thus described my invention, I claim:

1. A folded dipole antenna comprising a mast, a cube-like first element surmounting said mast, cube-like second elements disposed in contiguity with said first element, each of said second-named elements having post-like members formed integrally therewith extending horizontally from opposite faces thereof, tubular rods connected to said extensions, and end plates connected to the ends of said tubular rods.

2. An antenna comprising a mast, a cube-like element surmounting said mast, cube-like elements in vertical tier arrangement disposed above said first-named element, each of said second-named elements having post-like members formed integrally therewith and extending horizontally from opposite faces thereof, and crossed folded dipoles connected to said post-like members and arranged to produce an omnidirectional field pattern.

3. A folded dipole antenna comprising a mast, a cube-like element surmounting said mast and having a horizontally disposed threaded opening therethrough, cube-like elements disposed adjacent said first-named element, each of said second-named elements having post-like extensions formed integrally therewith extending horizontally from opposite faces thereof and each having also a threaded opening extending therethrough in axial alignment with the threaded opening of said first-named element, a single threaded rod extending through all of said threaded openings and interconnecting all of said elements, tubular rods connected to said extensions, and end plates connected to the ends of said tubular rods.

4. An antenna comprising a mast, a cube-like element surmounting said mast, cube-like elements in vertical tier arrangement disposed above said first-named element, each of said second-named elements having post-like members formed integrally therewith and extending horizontally from opposite faces thereof and having also threaded openings extending vertically therethrough, a single threaded rod extending through all of said threaded openings and interconnecting all of said elements with each other and with said first-named element, and crossed folded dipoles connected to said post-like members and arranged to produce an omnidirectional field pattern.

WESLEY C. MOCK, JR.
